UNITED STATES PATENT OFFICE.

WILLIAM GEORGE ABBOTT, JR., OF WILTON, NEW HAMPSHIRE.

RECOVERY OF INGREDIENTS FROM WOOL-SCOURING AND ANALOGOUS LIQUORS.

1,110,277.

Specification of Letters Patent.

Patented Sept. 8, 1914.

Application filed January 2, 1913. Serial No. 739,597.

To all whom it may concern:

Be it known that I, WILLIAM G. ABBOTT, Jr., a citizen of the United States, and resident of Wilton, in the county of Hillsborough and State of New Hampshire, have invented new and useful Improvements in Recovery of Ingredients from Wool-Scouring and Analogous Liquors, of which the following is a specification.

10 My invention relates to the recovery of valuable ingredients from solutions, emulsions and suspensions, of which a conspicuous example is found in wool scouring liquor, and has for its object the separating 15 of the greasy constituents from the liquor without the employment of relatively expensive refining processes.

In the accompanying drawings, which illustrate apparatus by aid of which my invention may be utilized,--Figure 1 is a front elevation of the separator; and Fig. 2 is a side elevation of the separator.

This apparatus which is illustrated in a very simple form is in effect a digester composed of a cylindrical body B surmounted by a dome C, and terminating at its lower end in a cone D. At about the middle height of the cylinder B, the test chamber E is attached by means of the pipes Q and R which, under the control of valves S and T, afford means of communication between the digester and the test chamber E. This test chamber is provided with a sight glass F. A gage glass G serves to indicate the upper level of liquid in the digester, a pressure gage H is applied to indicate the internal pressure, and the following system of pipes is attached to the apparatus.

40 The liquor inlet pipe M and outlet pipe N controlled by suitable valves (in this instance not shown) serve to introduce and withdraw liquor from the digester. A steam inlet pipe J and steam outlet pipe K communicate with an interior steam coil, 45 shown in dotted lines at L. A drain pipe O is inserted at the apex of the cone D and is controlled by the valve P. A scum outlet pipe is provided at I.

50 A vent valve, as at U, serves to vent the air from the interior of the digester when necessary, and a safety valve (not shown) may be provided if desired.

My new process is carried out in the apparatus above described as follows: Wool

scouring liquor is introduced through the pipe M, the vent valve U being open to allow the digester to be filled. When the level of wool scouring liquor shows in gage glass G, the supply is cut off and the vent valve U closed. All the pipes communicating with the interior of the digester being closed, steam is admitted at J, circulating through the coil L and emerging through pipe K, and the liquor is heated to 160° to 170° centigrade. The pressure in the digester at this temperature will not be far from 110 pounds. The grease particles become coagulated by reason of the heat and circulate rapidly with the liquor; the coagulation of the greasy particles will be apparent by observation of the sight glass F attached to the test chamber E, in which (valves S and T being open) the liquor is heated by circulation.

The progress of the process may be tested 75 by closing the valves S and T, and therefore allowing the liquor in the test chamber E to cool off. As it cools the circulation becomes less violent, and if the liquor in the sight glass F clears by the settling of coagulated grease, it is evident that the heating in the digester has continued long enough. The steam circulation is then cut off, the body of liquor in the digester cools and the slow convection currents carry the 80 grease particles into the cone D, where the heaviest matter and dirt has already settled, forming a mass sharply distinguished from the liquor out of which the grease particles settle as cooling proceeds. Some of the 85 greasy constituents, principally the neutral portions, rise to the surface of the liquor in the digester and there form a fluid layer free from dirt. The different separated products can now be tapped off. The top 90 grease is drawn off through the scum outlet pipe I; this should preferably be drawn off while the digester is still fairly hot. The liquor outlet pipe N is next opened, and after the blowing off of any grease that may 95 have happened to settle in it, the liquor containing the potash salts and the soluble greases runs out clear and dark colored. After the liquor has been drawn through the pipe N, the heavy greases and dirt can 100 be run through pipe O. These greases are a thick viscid mass that usually jellies on 105 cooling.

The products thus separated may be treated in various ways to make them marketable.

I claim:

5 1. The method of separating the constituents of wool scouring and analogous liquors, which consists in subjecting the liquor to heat under pressure until the lighter fatty substances and the heavier 10 greases become segregated in the liquor, the former rising to the top and the latter settling in coagulated form to the bottom.

2. The method of separating the constituents of wool scouring and analogous 15 liquors, which consists in heating the liquor to about 165° centigrade under pressure until the lighter and heavier greasy substances have separated in the liquor, the former rising to the top and the latter settling in coagulated form to the bottom.

20 3. The method of separating the constituents of wool scouring and analogous

liquors, which consists in subjecting the liquor to heat under pressure until the lighter fatty substances and the heavier 25 greases become segregated in the liquor on cooling, the former rising to the top and the latter settling in coagulated form to the bottom.

4. The method of separating the constituents of wool scouring and analogous 30 liquors, which consists in heating the liquor to about 165° centigrade under pressure until the lighter and heavier greasy substances segregate in the liquor on cooling, 35 the former rising to the top and the latter settling in coagulated form to the bottom.

Signed at Boston, Massachusetts, this eighteenth day of December 1912.

WILLIAM GEORGE ABBOTT, JR.
